UNITED STATES PATENT OFFICE.

LASSAR J. GRINBERG, OF NEW YORK, N. Y.

STOVE-LEG FASTENING.

No. 855,567.

Specification of Letters Patent.

Patented June 4, 1907.

Application filed March 26, 1907. Serial No. 364,593.

To all whom it may concern:

Be it known that I, LASSAR J. GRINBERG, a citizen of the United States, residing at New York city, Manhattan, county and State of New York, have invented new and useful Improvements in Stove-Leg Fastenings, of which the following is a specification.

This invention relates to simple and reliable means for removably attaching the legs to the base-plate of gas, oil and other stoves.

In the accompanying drawing: Figure 1 is a vertical section, partly in side view, of my improved stove leg fastening; Fig. 2 a bottom view of part of the base-plate, showing one member of the fastening; Fig. 3 a section through the fastening complete, on line 3—3, Fig. 2; Fig. 4 a similar section on line 4—4, Fig. 2, and Fig. 5 a perspective view of the top of a stove leg, showing the second member of the fastening.

The base-plate 10 of the stove has a circumferential downwardly extending flange 11. Near each corner there is cast on the bottom of the base-plate a socket 12, set in an oblique direction with relation to the base-plate. This socket has a diagonal slot 13 and a projection 14 opposite said slot. The socket opens toward the corner of the base-plate and constitutes the first member of the fastening.

The stove leg 15 has an upper flange 16, from the corner of which projects inwardly a lug 17 having a diagonal slot 18, such lug

constituting the second member of the fastening. The co-relation between the parts is such that when they are assembled, slot 18 will extend directly beneath slot 13, and will embrace projection 14.

In use, a bolt 19 is passed with its head 20 into the socket 12, so that its shank extends downwardly through slot 13. Leg 15 is now placed in position with its flange 16 bearing against flange 11 of plate 10, and its slot 18 embracing projection 14. Slot 18 becoming 45 thus alined with slot 13, bolt 19 will pass also through the former, its exposed free end being finally engaged by a nut 21, which securely locks the leg to the base plate. It will be seen that by the means described a 50 reliable fastening is provided which permits the leg to be readily attached and removed, and is entirely invisible when the stove is in its normal position.

I claim:

In a stove leg fastening, a flanged stove plate having a slotted socket and a projection on the socket, combined with a flanged stove leg having a slotted lug adapted to embrace said projection, and with a bolt engaging the 60 socket and lug, substantially as specified.

Signed by me at New York city, (Manhattan,) N. Y., this 25th day of March, 1907.

LASSAR J. GRINBERG.
